UNITED STATES PATENT OFFICE.

CONSTANT FICQ, OF VICTORIA, BRITISH COLUMBIA, CANADA.

ELECTRIC LAMP.

1,149,038.

Specification of Letters Patent. Patented Aug. 3, 1915.

Application filed February 14, 1914. Serial No. 818,739.

To all whom it may concern:

Be it known that I, CONSTANT FICQ, a citizen of Canada, residing at Victoria, in the Province of British Columbia and Dominion of Canada, have invented new and useful Improvements in Electric Lamps, of which the following is a specification.

The invention relates to electric lamps of the incandescent type, the purpose being to prevent the loss of luminous rays and to direct the same in a manner to obtain greater efficiency from a given amount of current.

In accordance with this invention the lamp comprises a base which presents an extended reflecting surface, such base receiving a globe and having the filament attached thereto and extended so as to present a maximum amount of light giving surface.

The invention consists of the novel features, details of construction and combination of parts, which hereinafter will be more particularly set forth, illustrated and claimed.

In the drawings hereto attached: Figure 1 is a view in elevation of an incandescent lamp embodying the invention. Fig. 2 is a vertical central section. Fig. 3 is a view of the lamp inverted.

Corresponding and like parts are referred to in the following description, and indicated in all the views of the drawing, by the same reference characters.

The lamp comprises a base and a globe, the latter being transparent and the base being constructed of porcelain or other vitreous material of a nature so as not to transmit rays of light. The base comprises a stem 1 and a body 2, the latter being extended and preferably of circular form. A groove 3 is formed in the outer portion of the body 2 near its edge and is intended to receive the edge of the globe 4 which is secured to such groove by means of cement. The side of the body 2 facing the globe 4 constitutes a reflecting surface and serves to throw the rays of light in one direction, thereby concentrating the luminous rays and preventing their waste in a direction opposite that required for use. The conductors 5 are preferably molded within the base and are connected respectively to the sleeve and button so as to make electric connection with the corresponding parts of the socket when the lamp is fitted to such socket in the manner well understood. The filament 6 is

connected at its extremities to the conductors 5 and extends across the reflecting surface of the base in a zig zag direction as shown most clearly in Fig. 3. A plurality of pins 7 are let into the base and constitute supports for the loops or folded portions of the filament. The pins 7 have eyes at their lower ends to receive the return elements of the filament, thereby supporting the return or folded portions intermediate of their ends. As a result of this construction, the lamp is adapted to withstand a shock without causing fracture of the filament. The reflecting surface of the base may be finished in any manner so as to direct the rays of light to the best advantage for use.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention, what is claimed as new is:—

An incandescent electric lamp comprising a base of vitreous material comprising a stem having formed integral at one end thereof a relatively thin laterally extending annular flange having an annular groove near its periphery, the under surface of said flange constituting a reflector, a filament comprising a plurality of folds or loops arranged within the reflecting surface of the base, supports for the loops or folds of the filament let into the base, a globe semi-circular in vertical section having its peripheral edge portion seated in the groove, and an adhesive material interposed between the wall of said groove and the outer surface of the edge portion of said globe.

In testimony whereof I affix my signature in presence of two witnesses.

CONSTANT FICQ.
